S. L. PARR

GRATE

Filed May 20, 1924

Fig. 1.

S. I. Parr, Inventor

334 Clarence A. T. Brian.

Attorney

UNITED STATES PATENT OFFICE.

SILAS L. PARR, OF OSHKOSH, WISCONSIN.

GRATE.

Application filed May 20, 1924. Serial No. 714,642.

To all whom it may concern:

Be it known that I, SILAS L. PARR, a citizen of the United States, residing at Oshkosh, in the county of Winnebago and 5 State of Wisconsin, have invented certain new and useful Improvements in a Grate, of which the following is a specification.

This invention relates to new and useful improvements in grates for stoves or furnaces and has for its principal object to provide a grate structure wherein means are provided for pivoting the grate, means being further provided for oscillating the grate.

Another important object of the present 15 invention is to provide a grate of the above mentioned character, which is of such a construction as to enable the same to be easily and efficiently operated whereby clinkers, ashes, slate or stone may be removed from 20 the fuel in the fire box without interfering with the burning of the fuel.

A further object of the invention is to provide a grate of the above mentioned character, which is simple in construction, 25 inexpensive, strong and durable and furthermore adapted for the purposes for which it is designated.

Other objects and advantages of this invention will become apparent during the 30 course of the following description.

In the accompanying drawing forming part of this specification and in which like numerals designate like parts throughout the same:—

35 Figure 1 is a vertical sectional view of the lower portion of a furnace showing my improved grate associated therewith in section and also showing the operating means therefor, the section being taken substantially on the line 1—1 of Figure 2 and

Figure 2 is a top plan view of Figure 1.

In the drawing wherein for the purpose of illustration is shown the preferred embodiment of my invention, the numeral 1 45 designates a supporting ring which is pivotally supported below the fire pot or box 2 and directly above the ash pit 3 on the trunnions 4 which are arranged at diametrically opposite points in the manner clearly 50 illustrated in Figure 2 of the drawing. The supporting ring is further provided with spider arms 5 and the purpose thereof will hereinafter be more fully described.

Supported on the upper edge of the ring 55 1 is the grate 6 and the same is provided on its under side with downwardly extending

ears which are arranged at diametrically opposite points on the grate and extend adjacent the outer edge of the ring 1 in the manner clearly illustrated in the drawing. 60 For the purpose of supporting the grate 6 in position on the ring 1 I provide the diametrically extending bar 8 the ends of which extend through diametrically opposed openings provided in the depending ears 7 and 65 any suitable fastening means such as shown at 9 is adapted to extend through each end of the bar 8 for preventing the displacement of the same from the ears 7. It is also to be understood that the bar 8 is disposed directly below the lower edge of the 70 supporting ring and preferably the bar is adapted to abut the lower edge thereof.

The spider portion of the supporting ring 1 is provided with an upwardly extending projection 10 and the same fits in a cylindrical socket 11 provided in the central portion 12 of the underside of the grate 6 in the manner clearly illustrated in Figure 1. The purpose of this construction will 80 also be hereinafter more fully described.

Secured to the supporting ring 1 and depending therefrom is the rocker arm 13. The lower end of the rocker arm is pivotally connected to the inner end of the horizontally extending elongated link 14 shown at 15 in the drawing. The outer end of the link 14 extends through the ash pit 3 and is pivotally connected to the lower end of an operating lever 16 in the manner shown 90 at 17. This construction provides a means whereby the supporting ring 1 and the grate 6 mounted thereon may be tilted on the trunnions 4 so that a pivotal movement of 95 the grate is obtained.

For the purpose of holding the supporting ring and grate at any desired angle, I provide the toothed segment 18 which is supported by the furnace A and to which is pivoted the lever 16 in the manner shown 100 at 19. A pawl 20 associated with the lever 16 for engagement with the teeth on the segment and an auxiliary handle such as is shown at 21 is provided for the pawl for releasing the same from engagement with 105 the segmental teeth in the manner well known in the art.

For the purpose of oscillating the grate 6, I provided the latter with a depending arm 22 which is arranged at a point adjacent the 110 rocker arm 13 and is preferably off center so as to enable the grate to oscillate on the

supporting ring 1. The lower end of the arm 22 is connected to the inner end of an elongated link 23 similar to the elongated link 14 and if desired, a ball and socket joint 5 such as is shown at 24 provides the connection between the inner end of the elongated link 23 and the arm 22. An operating lever 25 is pivotally connected at its lower end to the outer end of the link 23 and is 10 furthermore pivotally supported on the segmental bracket 18 on the opposite side of the lever 16.

When it is desired to oscillate the grate 6, the lever 25 is actuated to cause a forward 15 and rearward movement of the arm 22, the grate resting on the upper edge of the supporting ring 1 and having the socket portion 11 receiving the central projection 6, the same will act as a bearing whereby the 20 grate may oscillate on the ring without interfering with the supporting ring or causing movement thereof.

It will thus be seen from the foregoing description, that a grate has been provided 25 wherein the same may be either tilted or oscillated for enabling clinkers, stones, slate or ashes to be removed from the burning fuel in the fire box in a simple and efficient manner. The operating means is further- 30 more arranged on the outside of the furnace so as to enable a person to conveniently actuate the same.

A grate structure of this character may 35 be manufactured at a very low cost and will further be strong and durable.

While I have shown the preferred embodiment of my invention, it is to be understood that various changes in the size, shape and arrangement of parts may be resorted to 40 without departing from the spirit of the invention and the scope of the appended claims.

Having thus described the invention, what 45 I claim is:—

45 1. A grate structure comprising a supporting ring pivotally supported in a furnace, a grate supported on the upper edge of said ring, depending ears arranged at diametrically opposite points on said grate 50 and disposed adjacent the outer edge of the supporting ring, a bar extending through

openings provided in the ears, fastening means therefor, means for tilting said ring and the grate supported thereon comprising a rocker arm secured at its upper end to the 55 supporting ring, a horizontally disposed link pivotally connected at its inner end to the lower end of the rocker arm, and means connected to the outer end of the link for actuating the same. 60

2. A grate structure comprising a supporting ring pivotally supported in a furnace, a grate supported on the upper edge of said ring, depending ears arranged at diametrically opposite points on said grate and disposed adjacent the outer edge of the supporting ring, a bar extending through openings provided in the ears, fastening means therefor, means for tilting said ring and the grate supported thereon comprising a rocker arm secured at its upper end to the 65 supporting ring, a horizontally disposed link pivotally connected at its inner end to the lower end of the rocker arm, means connected to the outer end of the link for actuating the same, and means for oscillating 70 the grate on said supporting ring. 75

3. A grate structure comprising a supporting ring pivotally supported in a furnace, a grate supported on the upper edge 80 of said ring, depending ears arranged at diametrically opposite points on said grate and disposed adjacent the outer edge of the supporting ring, a bar extending through openings provided in the ears, fastening 85 means therefor, means for tilting said ring and the grate supported thereon comprising a rocker arm secured at its upper end to the supporting ring, a horizontally disposed link pivotally connected at its inner end to the 90 lower end of the rocker arm, means connected to the outer end of the link for actuating the same, means for oscillating the grate on said supporting ring, said last mentioned means comprising an arm depending 95 from the grate at a point adjacent the center thereof, a horizontally disposed link connected at its inner end to the lower end of said arm, and means connected to the outer end of said link for actuating the same. 100

In testimony whereof I affix my signature.

SILAS L. PARR.
